UNITED STATES PATENT OFFICE.

HENRY A. BATES, OF MIDDLETOWN, CONNECTICUT.

SEWING-MACHINE SHUTTLE.

No. 908,888.

Specification of Letters Patent.

Patented Jan. 5, 1909.

Application filed May 27, 1908. Serial No. 435,185.

To all whom it may concern:

Be it known that I, HENRY A. BATES, a citizen of the United States, residing at Middletown, in the county of Middlesex and State of Connecticut, have invented an Improvement in Sewing-Machine Shuttles, of which the following is a specification.

My invention relates particularly to the tension or holding spring of the thread bobbin, and the same is an improvement upon the devices of patents heretofore granted to me in this art.

In the device of my present invention I preferably employ a form of sewing machine shuttle in which there is a pivoted lever secured to a slotted tubular pin of the bobbin case holder or shell over which the bobbin case is passed, and this lever turns down to connect these parts. With this device it is difficult to separate the parts and particularly to remove the thread bobbin from the bobbin case after the latter has been slipped over the lever; ordinary springs not having sufficient resiliency and movement to assist in this separation. In the device of my invention and in combination with this bobbin case holder or shell and a separable bobbin case and thread bobbin, I employ a volute spring adapted to be received within the bobbin case and seated against the inner angular corner thereof. The spring is coiled for compression in the direction of the axis of the bobbin case. Its convolutions are therefore adapted to be brought into the same plane or substantially so by introduction into the bobbin case of the thread bobbin; the resiliency of the spring still being fully effective the moment the connecting pressure of the lever is removed,—the action being not only to separate the bobbin case from the bobbin case holder but the thread bobbin from the bobbin case.

In the drawing Figure 1 is a plan of the sewing machine shuttle such as I prefer to employ. Fig. 2 is a plan of the bobbin case holder or shell; the bobbin case being removed and the pivoted lever turned up into the axial line of the tubular pin. Fig. 3 is a plan of the bobbin case with the spring of my improvement without the thread bobbin and as turned directly over from its relation with the bobbin case holder as shown in Fig. 2. Fig. 4 is a cross section on the dotted line $x-x$, of Fig. 1 showing the transverse section of the parts shown in Figs. 1 to 3 inclusive and also of the thread bobbin. Fig. 5 is a vertical

cross section on the dotted line $y-y$, of Fig. 3 through the bobbin case and its spring alone.

The bobbin case holder or shell a comprises a disk with a flange that is narrow in part and wide in part with a hook a^1 and a central tubular pin a^2 slotted along one side; the said pin being longer than the thickness of the bobbin case c .

In the outer end of the tubular pin a^2 a lever b is pivotally connected by the pin 2 and within this tubular pin is a plunger 4 and a spring 3 between the under side of the head of the plunger and the inner surface of the bobbin case holder a ; the function of the spring plunger being to maintain the lever b in either one of its two positions, that is to say, the inner end of the lever head where it is pivoted to the tubular pin is beveled in opposite directions so that when one face of the bevel comes against the flat face of the plunger the lever is held down against the bobbin case as shown in Fig. 4. If upon the other hand this lever is pulled outward into an axial line with the tubular pin a^2 the other inclined face comes to a bearing upon the outer surface of the plunger and it is then held in line to the tubular pin so that the bobbin case and thread bobbin may be slipped on or off of the tubular pin into its operative position or separate therefrom.

The bobbin case c is a shell cup-shaped, and is provided with a central opening c^1 to receive the free end of the tubular pin a^2 which passes therethrough. This bobbin case is preferably provided with a thread tension device e of usual construction and f represents the thread bobbin received within the bobbin case which it closely fits; the opening in the thread bobbin being concentric with the opening in the bobbin case.

The essential feature of my invention resides in the volute spring d having a large base convolution 5 and a small top convolution 6, and as will be seen from Fig. 5 this spring when free fills more than half the depth or thickness of the bobbin case. It is coiled for compression in the direction of the axis of the bobbin case so that it would lie down in a plane parallel with the plane of the base of the bobbin case or substantially against the inner flat surface of the bobbin case without its resiliency being affected. It is removable and is frictionally held by the large base convolution being pressed into the inner corner or angle of the bobbin case. The thread bobbin f fits the bobbin case com-

paratively freely and yet sufficiently closely for it to maintain its concentricity therewith. When the thread bobbin is placed into the bobbin case this volute spring is put under tension and brought into an almost flattened condition; especially is this the case when the tubular pin of the bobbin case holder is passed through the thread bobbin and through the open center *c* of the bobbin case. 10 In this position and when the lever *b* is turned over as shown in Fig. 4, the parts are connected in a removable relation, but this connected relation cannot be changed except by normally swinging the lever *b*. Fig. 15 4 shows the volute spring *d* under tension and with the convolutions in substantially a flat horizontal plane. The moment the lever *b* is turned from the full line position Fig. 4 into the dotted position Fig. 4 the bobbin 20 case and thread bobbin are released. The power of the spring *d* is then at once manifest, causing the separation or disassociation from their operative position of the bobbin case from the thread bobbin and from the 25 bobbin case holder so that the continuation of the act of separating the parts can be readily and easily performed manually. By means of this volute spring an even tension is applied to the un-winding thread of the 30 bobbin and this tension is permanent because of the liberal proportions of the volute spring *d* and the further fact that the same is not at all liable to be injured in use. The 35 overlapped central convolution of the volute spring shown at 6 provides a convenient seat for the thread bobbin at one side.

I claim as my invention:

1. The combination with a bobbin case holder, a bobbin case and thread bobbin received thereby and means for connecting said parts, of a volute spring received in the bobbin case between the same and the thread bobbin and acting expansively upon the release of said means to separate said parts.
- 45 2. The combination with a bobbin case holder, a bobbin case and thread bobbin received thereby and means for connecting said parts, of a volute spring coiled for compres-

sion in the direction of the axis of the bobbin case received in the bobbin case between the 50 same and the thread bobbin and acting expansively upon the release of said means to separate said parts.

3. The combination with a bobbin case holder, a tubular slotted pin formed therewith and a lever pivoted in the open free end of the tubular pin, of a bobbin case having an open center adapted to be passed over said lever and tubular pin, and said parts held together by the operation of said lever, a thread 60 bobbin received within the bobbin case and a volute spring also received within the bobbin case and between the same and the thread bobbin and acting expansively upon the release of said means to separate said parts. 65

4. The combination with a bobbin case holder, a tubular slotted pin formed therewith and a lever pivoted in the open free end of the tubular pin, of a bobbin case having an open center adapted to be passed over said 70 lever and tubular pin and said parts held together by the operation of said lever, a thread bobbin received within the bobbin case, and a volute spring coiled for compression in the direction of the axis of the bobbin case also 75 received within the bobbin case and between the same and the thread bobbin and acting expansively upon the release of said means to separate said parts.

5. The combination with a bobbin case holder, a bobbin case and thread bobbin received thereby and means for connecting said parts, of a volute spring received in the bobbin case between the same and the thread bobbin and acting upon the thread bobbin to 85 prevent a too free unwinding or loosening of the thread when the parts are connected, and also acting expansively upon the release of said connecting means to separate the bobbin case from the remaining parts. 90

Signed by me this 21st day of May 1908.

HENRY A. BATES.
